J. M. DOWNING.
WATER FEED FOR ACETYLENE LAMPS.
APPLICATION FILED MAY 23, 1914.

1,119,936.

Patented Dec. 8, 1914.

UNITED STATES PATENT OFFICE.

JOHN M. DOWNING, OF EAST ST. LOUIS, ILLINOIS.

WATER-FEED FOR ACETYLENE-LAMPS.

1,119,936.

Specification of Letters Patent.

Patented Dec. 8, 1914.

Application filed May 23, 1914. Serial No. 840,578.

To all whom it may concern:

Be it known that I, JOHN M. DOWNING, a citizen of the United States, and resident of East St. Louis, Illinois, have invented 5 certain new and useful Improvements in Water-Feed for Acetylene-Lamps, of which the following is a specification containing a full, clear, and exact description, reference being had to the accompanying drawings, 10 forming a part hereof.

My invention relates to an improved water feed for acetylene lamps, and consists in the novel construction hereinafter described and specifically designated in the appended 15 claims.

The object of my invention is to provide an improved water feed for acetylene lamps, wherein the water will be fed to the carbide by more accurate and efficient means than 20 have been used in lamps heretofore known to me.

Heretofore in miner's acetylene lamps there has been much difficulty in efficiently regulating the water feed and an additional 25 object of my invention is to remedy such defects in said lamps.

In the drawings: Figure 1 is a sectional side elevation of a miner's acetylene lamp having my invention applied thereto; Fig. 2 is an enlarged sectional plan view taken on the line 2—2 of Fig. 1; Fig. 3 is an enlarged sectional plan view taken on the line 3—3 of Fig. 1; Fig. 4 is an enlarged vertical section of the details of the water feed tube 35 and its connections, and Fig. 5 is a sectional plan view taken on the line 5—5 of Fig. 4.

Referring by numerals to the accompanying drawings: 6 indicates the usual water receptacle having the filling cap 7 and the hook 8, by means of which the lamp is attached to the miner's cap, and said water receptacle is mounted above the usual carbide container 9. The numeral 10 indicates the 45 water tube, which extends vertically through the said water receptacle 6 and through the bottom plate 11 thereof, and projects downwardly within said carbide container 9. Upon the lower end of said water tube 10 is loosely mounted to slide a guard sleeve 12, the lower end of which sleeve is provided with suitable water exits 13. Small 50 exit apertures 14 are also formed in said sleeve at a point some distance above its lower end. Mounted within said water tube 10 is the valve stem 15, which is threaded

at its upper end and has screwed on said threaded portion a handle 16 which bears against the upper end of said tube 10 to adjust the valve 17 which is formed upon or 50 secured to the lower end of said valve stem, and said valve is adapted to control the exit of water from the lower end of said tube. The numeral 18 indicates a coil spring, which is mounted upon the exterior of said 55 water tube 10 within said carbide container 9, and the upper end of said spring bears against a perforated strainer plate 19, and the lower end of which spring bears against the upper end of said guard sleeve 12, for 60 the purpose of urging the lower end of said sleeve into contact with said valve 17, and also for the purpose of retaining the said strainer plate 19 in contact with a filter disk 20, which is located between said strainer plate and said bottom 11 of the said water 65 receptacle. The bottom 11 of said water receptacle is provided with a gas exit 21, which communicates with the interior of a gas passage 22. A burner tube 23 is connected to the lower portion of said water receptacle, so that the interior of said tube 70 is in communication with said gas passage 22, and a common burner tip 24 is located as usual in the outer end of said burner tube. The usual reflector 25 is mounted upon said 75 burner tube. Depending from the lower end of said water receptacle 6 is the usual cap for the said carbide container 9, and said cap is provided with the usual threads 26 80 for engaging like threads 27 formed on the neck at the upper end of said carbide container, and a suitable gasket 28 is clamped 85 between the said cap and the body of said container for the purpose of making a tight 90 joint between the said parts. 29 indicates a lug forming a handle on the under side of said strainer plate 19. Formed in the said water tube 10 adjacent the bottom of said water receptacle 6 is a feed opening 30, 95 whereby water may pass from said water receptacle to the interior of said water tube. The said valve stem 15 is provided with a flattened portion 31 at its lower end and the lower portion of said water tube is 100 correspondingly flattened upon its interior, 105 to prevent turning of the said valve stem during operation.

The operation of my invention will be obvious to those skilled in the art, and need 110 not be further explained, except to say that whenever it is desired to feed the water from

the said water receptacle to the carbid contained in the carbid container, it will only be necessary to rotate the said handle 16 upon the threaded valve stem 15, thereby unscrewing the said handle and allowing the said spring 18 to force downwardly the said guard sleeve 12, and it in turn will force open the valve 17, allowing water to pass out of the lower end of said water tube 10 and thence through the water exits 13 to the carbid contained in said carbid container, when the gas will be generated in the usual way and pass upwardly, through the perforations of the said strainer plate 19, thence to the gas exit 21, thence to the gas passage 22 and the burner tube 23.

From the above it will be seen that my improved construction permits the water to be fed to the carbid in a very accurate and efficient manner, and that the regulation of the water may be very accurately controlled.

In practice, should the lower water exits 13 become clogged by the ashes, the water can still make its exit through the small apertures 14.

One of the principal advantages of my invention is the ready removal of the valve stem and other parts for the purpose of cleaning same, and it will be readily seen that by detaching the handle 16 the said valve stem may be readily withdrawn from the water tube 10 and the valve guard sleeve 12, and the spring 18, and strainer plate 19 may be readily cleaned and replaced. The said spring 18 places a tension on the said handle 16 by forcing said valve stem down-

wardly at all times, and thereby retains said handle in any position at which it may be adjusted, and prevents it being jarred loose during use.

40

I claim:

1. In an acetylene lamp, a water receptacle, a carbid container, a tube extending through said water receptacle into said carbid container, a valve-stem located within said tube, means for preventing the turning of said stem within said tube, a valve at the lower end of said stem to close the lower end of said tube, a sleeve loosely mounted on said tube, in engagement with the said valve, a spring for urging said sleeve into contact with said valve to force the valve open, and a suitable handle for moving said stem upwardly in closing said valve.

2. In an acetylene lamp, a water receptacle, a carbid container, a tube extending through said water receptacle and into the carbid container, a valve stem and valve mechanism detachably connected to said parts and adapted to be removed therefrom for cleaning purposes, a guard sleeve loosely mounted on said water tube within said carbid container, a valve at the lower end of said stem, and a spring for urging said sleeve into contact with said valve.

In testimony whereof, I have signed my name to this specification, in presence of two subscribing witnesses:

JOHN M. DOWNING.

Witnesses:

E. L. WALLACE,
JOHN C. HIGDON.
